S. WEINRIB

INDIVIDUAL TOOTHBRUSH STERILIZER

Filed April 4, 1924

Inventor
Samuel Weinrib

By Attorney *William S. Gluck*

UNITED STATES PATENT OFFICE.

SAMUEL WEINRIB, OF NEW YORK, N. Y.

INDIVIDUAL TOOTHBRUSH STERILIZER.

Application filed April 4, 1924. Serial No. 704,202.

To all whom it may concern:

Be it known that I, SAMUEL WEINRIB, a citizen of the United States, and a resident of the city, county, and State of New York, 5 have invented certain new and useful Improvements in an Individual Toothbrush Sterilizer, of which the following is a specification.

My present invention relates generally to 10 a tooth brush holder and sterilizer and more particularly to an arrangement whereby I provide an individual container for the toothbrush so arranged and constructed as to automatically sterilize the toothbrush that 15 is contained therein.

It is a well-known fact that tooth brushes even before being used and more particularly after having been used, exhibit to a marked degree the presence of germ life of 20 various characters. In addition to this, the arrangement commonly employed whereby a number of toothbrushes are suspended or held in closely adjacent position as to permit them to contact necessarily is an extremely 25 unhygienic one, and is not conducive to the well-being of the individual who uses a toothbrush.

One of the important objects of my invention, therefore, is to provide in the first 30 place, an arrangement whereby individual containers are provided for each brush, and in addition, an arrangement whereby the toothbrush contained therein is automatically sterilized while in position in the container. Attempts made hitherto to attain 35 such ends have been in the form of constructions which either in themselves are complicated, and therefore expensive to manufacture, and inconvenient to use, and in addition I have found that the sterilizing action of such container is ineffective for 40 a number of reasons.

Another important object of my invention, therefore, is a provision of a container 45 of this character, which will be simple in construction and efficient in operation.

As the problem of the size and contour of the container is an important one, arising 50 particularly from the fact that containers of this character occupy space at home, and particularly in travelling necessarily take up space in the travelling case or bag, one of the important objects of my invention is directed to making these containers not only 55 attractive in themselves, but also advanta-

geous from the standpoint of space which they occupy.

Another one of the important objects of my invention is the provision of an arrangement whereby on the one hand the insertion of the brush will induce an added sterilizing effect, and on the other hand, the removal of the brush, when it is desired to employ it, shall be as simple and automatic as 60 is possible.

The object of my invention, generally, is the provision of a simple, inexpensive combined arrangement which will form a container for a brush and which will, at the same time, automatically sterilize the brush 65 contained therein, and will permit of its ready insertion and removal therefrom.

For the attainment of these objects and of such other objects as may hereinafter appear or be pointed out, I have illustrated the 70 embodiments of my invention wherein—

Fig. 1 is a section longitudinally through the container showing the brush in position;

Fig. 2 is a section through the lower end 75 of the brush taken at right angles to the section along which Fig. 1 is taken;

Fig. 3 is a perspective view of the tablet which I employ;

Fig. 4 is a vertical section through the 80 lower end of a modified form of my invention, and

Fig. 5 is a perspective view of the lower end of such modified form with the tablet removed from the container body.

Upon viewing Fig. 1 it will be observed 85 that my container is preferably in the form of a cylindrical body 10, made of a material such as brass, and having its end 11 permanently closed and with its other end closed by a cover member 12 pivoted thereto by the 90 hinge 13.

The cap member 12 which may, if desired, be made of the same material as that of which the body member 10 is made, is provided with indentations or depressions 13, 100 two such depressions being illustrated in the drawings and positioned at points 180° removed from each other, although as will be understood, the objects of my invention will be effectively attained with a greater or lesser number. These depressions 13 may be formed in any desired or approved manner as by stamping and as will be observed upon viewing Fig. 2 of the drawing, they are 105 directed inwardly so as to constrict more or 110

less the width of the cap 12 for purposes that will shortly appear.

In Fig. 3, I show one form of a tablet 15 which I associate with the cap 12 and which 5 tablet may be in any desired or preferred form, such as a flat cylinder, and which tablet 15 is provided with cut out portions 16, positioned along the sides thereof 180° apart and are of a shape and contour so that when 10 the tablet is inserted into the cap, these cut out portions 16 can be made to register with the depressions 13 in the cap so as to permit the tablet 15 when so registered to pass these 15 depressions 13, the height of the tablet being such that the tablet as a whole will position itself wholly below the depressions 13.

When, therefore, the tablet 15 is inserted in the cap 12 in the manner pointed out, and the tablet given an axial movement with 20 reference to the cap so as to position the cut out portions 16 out of register with the depressions 13, the tablet will be held in the cap against accidental removal, and to make this arrangement more effective to prevent 25 such accidental falling out or removal, the height of the tablet 15 is so related to the position of the projections 13 above the bottom of the cap, that the top of the tablet 15 will be immediately below these projections 30 so that the tablet will be held in the cap so as to prevent the tablet having any free up and down movement therein.

Upon viewing Fig. 1, it will be observed that the hinge 13 is so positioned that when 35 the cap is swung about the hinge to its closed position, the lower end of the container body 10 will project into the cap 12 for a substantial distance, and by inturning the lower end of the body member inwardly as shown at 40 17, this lower end will tend to hold the tablet 15 in the cap should the tablet work around to a position where the cut out portions 16 register with the projections 13. This, I attain by bringing the lower end 45 of the cap to a position immediately adjacent the upper ends of the projections 13, as will clearly be understood when Fig. 2 is studied, and as shown in this figure, this lower end of the cap 17 is preferably positioned in contact with the projections 13 although this exact arrangement is not essential to attain broadly the functions which I 50 desire.

At the end of the body member 10 opposite to that to which the cap 12 is hinged and adjacent the closed end 11, I provide a suspension means such as the clip 19 arranged to suspend the container with the cap end 12 downwardly for purposes that will also appear.

In the employment of my invention, the toothbrush is inserted into the container through its bottom or open end with the bristle end 20 lowermost, and the cap 12 65 then moved to its closed position, in which

position the bristle head 20 will rest directly upon the tablet 15. The tablet 15 is in the form of a solid mass which contains chemicals of a character which will vaporize either normally, or more particularly in the 70 presence of water, and as will now be understood, the position of the brush in the holder as shown in Fig. 1 will tend to cause the drippings from the toothbrush bristles to fall upon the tablet 15 to make the sterilizing action of the tablet 15 particularly effective. In addition to this, the act of closing the container, as pointed out, will cause the brush to impact with a slight jar, the tablet 15 so as to still further increase 80 the sterilizing action.

By positioning the suspending means 19 at the permanently closed end 11 of the container, I have provided an arrangement whereby the brush is associated with the 85 tablet, as pointed out, and as illustrated in the drawing automatically, so that the employment of the suspending means for the brush positions the parts automatically, as desired. The removal of the brush from the container is also by my arrangement rendered particularly easy and effective, since with the container suspended by the clip 19, the act of moving the cap 12 about its pivot 90 13 to an open position will automatically 95 cause the brush to drop into the hand.

In Figs. 4 and 5, I have illustrated a modified form of my invention where I have the cap 12' take the form of a replaceable filler so that when it is desired to replace the 100 tablet 15, it can be done by merely removing the cap and substituting a new cap therefor. The filler 15' in Figs. 4 and 5 may be of the type shown in Fig. 3, and may be provided with cut out portions registering with depressions 13' in the cap, as in the modification as described, or may be in a form in which the filler is permanently associated with the cap 12', and I have illustrated in the drawings a preferred form whereby this 105 cap 12' can be associated with the container 10' as to be readily detachable therefrom and attachable thereto for replacement purposes.

Secured to this body member 10 in any 115 desired or preferred manner is the hinge 25 which has the hinge leaf or plate 26' hinged thereto and upon the outer face of this hinge leaf or plate 26' is the protuberance 27' which forms one element of a snap fastener, the other element 28' of which is positioned on the strap 29' secured to the outer surface of the cap, this strap 29' being bent outwardly as shown at 30' so as to provide a space 120 between such outwardly bent portion and the outer surface of the cap 12' sufficient to receive therewithin the hinge leaf or plate 26'.

When, therefore, the cap 12' and the container body 10' are assembled by forcing the cap on to the container body with the leaf 125

26' forced into the space referred to, the snap elements 27' and 28' will co-act to maintain this cap in position against accidental removal, and the hinge 13' will then serve as 5 a hinge for this cap just as does the hinge 13 for the cap 12 in the embodiment as described.

In this manner, I provide a cap which, on the one hand, acts in all respects like that 10 of the cap of Fig. 1 and at the same time which can be readily removed when it is desired to replace it with another cap having therein a new tablet.

Having thus described my invention and 15 illustrated its use, what I claim as new and desire to secure by Letters Patent is—

1. In a device of the character described, in combination a container adapted to receive and hold a toothbrush, a closure for 20 the container, means for pivotally supporting the closure from the container, said closure being in the form of a container adapted to hold and be recharged with a sterilizing agent, said pivotal mounting for the closure 25 permitting of the bodily removal and replacement of the closure whereby recharging of the closure container is facilitated.

2. In a device of the character described, in combination, a container adapted to receive and hold a toothbrush, a closure for the 30 container in the form of a container adapted to be recharged with and holding a sterilizing agent, a hinged member pivoted to the brush container and a separable association 35 between the closure and the hinged member whereby recharging of said closure member is facilitated by removal thereof.

3. In a device of the character described, in combination, a container adapted to receive and hold a toothbrush, a closure for 40

the container in the form of a container adapted to be charged with and removably holding therein a sterilizing agent, a hinged member pivoted to the brush container and a separable association between the closure 45 and the hinged member, said association comprising clasp elements on the pivoted hinge leaf or plate and on the closure, whereby recharging of said closure member is facilitated by removal thereof. 50

4. In a device of the character described, in combination, a container adapted to receive and hold a toothbrush, a closure therefor pivoted to the container and freely open thereto, said closure being in the form of a container and projections on the inside of the closure for holding therein a sterilizing agent, said projections being below the upper, outer edge of the container and the container having its lower end reduced in diameter and arranged to be received within the closure. 55

5. In a device of the character described, in combination, a container adapted to receive and hold a toothbrush, a closure therefor pivoted to the container, and freely open thereto, said closure being in the form of a container and projections on the inside of the closure for holding therein a sterilizing agent, said projections being below the upper, outer edge of the container and the container having its lower end reduced in diameter and arranged to be received within the closure, and said lower edge of the container being positioned adjacent the upper ends of 70 the projections. 75

In testimony whereof, I have hereunto signed my name.

SAMUEL WEINRIB.
